UNITED STATES PATENT OFFICE.

FREDERICK J. BACON, OF NEW LONDON, CONNECTICUT.

BANJO.

Application filed April 18, 1922. Serial No. 554,922.

This invention relates to improvements in stringed musical instruments and more particularly to an improvement in the resonance boxes of banjos, although the invention is not restricted to this particular type of stringed musical instruments.

The resonance box of the ordinary banjo is open at its back and as a consequence the sound waves are directed against the clothing of the player of the instrument and are somewhat deadened or muffled thus greatly detracting from the quality of the tone. Therefore it is the primary object of the present invention to overcome this difficulty and to provide means whereby the resonance of the instrument will be greatly increased and the quality of the tones greatly improved. In this connection also the invention has as its object to so construct the resonance box of the instrument that the tones will be materially amplified as well as improved in quality. In attaining these objects the invention has as its object the provision of a resonant back for the resonance box of the instrument which back will possess certain features of design and construction rendering it highly responsive to sound wave vibrations and adapting it to serve effectually as a medium for amplifying the sound waves and improving the tonal qualities.

By providing means for amplifying the sound waves delivered from the resonance box of the instrument, I especially adapt the instrument for concert use but as it may at times be desirable to render music in a more or less subdued tone, I contemplate arrangement of the resonant back of the resonance box within the open side of the box in such manner as to permit of its ready removal for this purpose.

Not only does the present invention have as its object the provision within the usually open back of the resonance box of a resonance sound wave amplifying medium which will respond to the sound wave vibrations and amplify the tones, but it also resides in so forming the wall of the box as to most effectually distribute and deliver the sound waves.

Another object of the invention is to so form the circumferential wall of the resonance box as to further enhance the quality of the tones and render this wall responsive to the sound wave vibrations and at the same time increase the responsiveness of the

membranous head of the resonance box to these vibrations.

In the accompanying drawings:

Figure 1 is a perspective view of a banjo constructed in accordance with the present invention; and

Figure 2 is a diametric sectional view through the resonance box thereof substantially on the line 2—2 of Figure 1 looking in the direction indicated by the arrows. 65

In the drawings the resonance box of the instrument is indicated in general by the numeral 1 and the neck of the instrument by the numeral 2, the latter being of the ordinary construction and connected in the usual manner with the resonance box. As previously stated the invention is not restricted to embodiment in a banjo, for the principles thereof may equally as well find embodiment in other stringed musical instruments of a 75 similar nature.

The resonance box 1, in the construction of which the invention primarily resides, comprises, as is usual, a circumferential wall indicated by the numeral 3 and which wall 80 may be made of any material found suitable for the purpose and is of the usual annular form. However this wall is, in its cross sectional dimensions, decreased in thickness from the back to the front of the 85 resonance box as clearly shown in Figure 2. This reduction in thickness may be effected by forming the rear portion of the wall of substantially uniform thickness as indicated by the numeral 4, and the forward portion 90 of the wall gradually thinned as indicated by the numeral 5, and preferably by beveling or flaring the inner surface of this portion of the wall, the outer surface of the wall retaining its usual cylindrical contour. 95 The advantage obtained by forming the wall 3 of the resonance box of decreasing thickness in the direction of the forward side of the box is that in this manner the responsiveness of the wall to sound wave vibrations is materially increased and the quality of the tones is enhanced. 100 This construction also presents a further advantage which will presently be pointed out.

The membranous head of the resonance box is indicated by the numeral 6 and the same comprises the usual calfskin membrane which is stretched at its marginal portion over the thinner front edge of the wall 3 of the box and suitably tensioned by a tension- 105 110

ing ring 7 applied about its said marginal portion and adapted to be drawn inwardly by the usual tensioning clamps 8 arranged at suitable intervals about the circumference 5 of the wall 3. Preferably the outer surface of the wall 3 is rabbeted or countersunk as at 9 so as to accommodate a metallic band 10 which is disposed about the thinner forward portion of the wall and has its forward 10 edge portion overturned in an inward direction or flanged as indicated by the numeral 11, the flange 11 being relatively narrow and engaging over the thin forward edge of said wall 3. Because of the reduced thickness 15 of the wall 3 at its forward edge, the calfskin head 6 when stretched over this edge of the wall will possess a greater degree of responsiveness to the sound wave vibrations than if this edge of the wall were 20 relatively thick, and this is the additional advantage referred to above as presented by the reduction in thickness of the wall in the direction of the forward side of the box. It will also be evident that the provision of 25 the flange 11 presents the advantage that by extending over the thin edge of the wall 3, splintering of this edge when the wall is made of wood, is effectually prevented.

The resonant sound amplifying medium 30 which chiefly constitutes the present invention, is indicated in general by the numeral 12 and the same comprises a circular head 13 preferably of wood, although other resonant material may be employed 35 for the purpose, and of a marginal contour and dimensions to adapt it to be fitted into the back of the sound box 1 which back is ordinarily left open in instruments of this type. Generally speaking, the head 13 is 40 of concavo-convex form, being concave upon its inner surface and convex upon its outer surface, and preferably the head at its middle portion 14 is of minimum thickness and is gradually increased in thickness as at 45 15 toward the periphery of the head. This peripheral portion which is indicated by the numeral 16 is relatively thick so that the head will be sufficiently substantial to adapt it to be firmly fitted into the open back of 50 the resonance box and also removed therefrom when desired without likelihood of distortion or injury. In order to adapt the head to be firmly frictionally fitted and held within the said open back of the box, a strip 55 17 of felt or other suitable material is secured by tacks or otherwise to the peripheral surface of the portion 16 of the head and the strip is then folded back upon itself as indicated by the numeral 18 and its other 60 edge portion 19 is brought over the inner face of the peripheral portion 16 of the head and preferably united thereto by adhesive or any other agent. By reason of the nature of the material of which the strip 17 is made, it provides a yielding frictional 65

means for obtaining a snug and firm fit of the member 12 within the open back of the resonance box and yet it permits of ready removal of the said member when this is desired. In order that the member 12 may 70 be readily placed in position and removed as occasion requires, finger knobs 20 are preferably secured upon the back or outer side of the head 13 near the periphery thereof and at diametrically opposite points. 75

From the foregoing it will be evident that the head 13 will be highly responsive to the sound waves propagated through vibration of the strings of the instrument and that these waves will be greatly amplified by reason of the resonant quality of the head, and in order to properly distribute the amplified waves in all directions and increase the quality of the tones, the wall 3 of the resonance box is preferably formed at intervals in its 80 circumference with sound openings 21, these openings being preferably located in the portion 5 of said wall, and the band 10 being formed with similar openings 22 which register therewith.

Where the term "front", or a similar term, is employed in this specification and in the claims, it is intended to designate the side of the body or resonance box to which the membranous head is secured, while the term "back", or the like, refers to that side of the resonance box or body which is open in banjos of ordinary construction.

Having thus described the invention, what is claimed as new is:

1. The combination with a stringed musical instrument of the type having a resonance box the back of which is ordinarily open, of an amplifier attachment therefor comprising a resonant sound amplifying head removably fitted within said back, the head being of minimum thickness at its central portion and of gradually increasing thickness in the direction of its periphery, and a friction element of yieldable material 105 covering the entire periphery of said head and in frictional contact with the inner side of the wall of the resonance box.

2. A stringed musical instrument having a resonance box comprising a circumferential wall thinned in the direction of one side of the box, a metallic band surrounding said wall and having a flange extending around the upper edge and engaging over the thinner edge of the wall, a membranous head stretched over the flange, and means on the wall for marginally engaging said head and securing the same.

3. A stringed musical instrument including a resonance box comprising a circumferential wall, a resonant sound amplifying head fitted into the back of the resonance box and having frictional contact throughout its entire periphery with the wall where- 125 by to be removably held, the said wall of the 130

box being decreased in thickness from its back to its front whereby the wall at the front of the box is relatively thin, and a membranous head stretched directly over and in contact with said thinner edge of the said wall, the thinned portion of the wall being provided with a circumferential series of radial openings therethrough.

4. An amplifying attachment for stringed musical instruments of the type having a resonance box the back of which is ordinarily open, the said attachment comprising a

resonant sound amplifying head of minimum thickness at its central portion and of gradually increasing thickness in the direction of its periphery and having its said periphery cylindrical, and a friction band secured to the periphery of the head and extending continuously about the same and constituting means for frictionally removably holding the head entirely within the back of the resonance box of the instrument.

In testimony whereof I affix my signature.
FREDERICK J. BACON. [L. S.]
